LESLIE A. RAWSON, OF LOS ANGELES, CALIFORNIA, ASSIGNOR TO EMSCO DERRICK & EQUIPMENT COMPANY, OF LOS ANGELES, CALIFORNIA, A CORPORATION OF CALIFORNIA

DOUBLE LEG CONSTRUCTION FOR DERRICKS

Application filed April 23, 1930. Serial No. 446,555.

My invention relates to a derrick such as is employed in the oil producing industry, having permanent main legs connected to the base and crown and removable auxiliary legs, 5 which main and auxiliary legs support the weight carried by the crown of the derrick. This design permits both the main and auxiliary legs to be used during the drilling of the well and the auxiliary legs to be removed 10 and only the main legs used during the pumping period, at which time only relatively light loads are imposed on the crown of the derrick. Derricks of this character form 15 part of the prior art, and the broad idea of a derrick having main and auxiliary legs, as outlined above, does not constitute my present invention.

In such derricks referred to, the load is proportioned on the main and auxiliary legs 20 by a manually operable means, and due to the reliance on the guesswork of the workman for proportioning the load it is never known whether or not the load is properly distributed on the legs. One of the common double 25 leg constructions provides an adjustment means in one of the legs whereby the leg may be lengthened and thus caused to carry a part of the load of the crown. The workman usually operates the lengthening means until 30 he thinks that the load is properly distributed. On many occasions the workman's judgment has been greatly in error, and intense strains have been placed on one of the legs to the injury of the derrick.

My invention provides a double leg construction for a derrick in which the main and auxiliary legs are automatically caused to carry predetermined proportions of the load carried by the crown of the derrick; and it 40 absolutely eliminates the human element which is involved in the making of the adjustments in the derricks of the prior art.

In the derrick of my invention the predetermined load which is to be carried by the 45 main and auxiliary legs is constant through-

out the use of the double legs in the derrick. Due to an equalizing means which constitutes a part of my invention, any slight distortion or settling of the derrick will not impair the operation of the legs, nor will it 50 change the proportions of the weight carried by the main and auxiliary legs.

The invention of this application is particularly concerned with the construction referred to in the two preceding paragraphs 55 having a means for permitting an easy installation or removal of the auxiliary leg.

Other advantages of my invention and the important features will be pointed out in the following description in which two forms of 60 my invention are illustrated.

In the accompanying drawings,

Fig. 1 is an elevational view illustrating a derrick incorporating the features of my invention.

Fig. 2 is a horizontal cross section taken on the line 2—2 of Fig. 1.

Fig. 3 is an elevational view in section, showing a double leg construction of my invention in which the equalizing means is in 70 the upper end of the derrick, and illustrates the main and auxiliary legs in operating position.

Fig. 4 is a view similar to Fig. 3 and shows the positions of the parts when the auxiliary 75 leg is removed.

Fig. 5 is an enlarged sectional view showing the equalizing means of Fig. 3.

Fig. 6 is a section taken on the line 6—6 of Fig. 5.

Fig. 7 is a section taken on the line 7—7 of Fig. 5.

Fig. 8 is a section taken on the line 8—8 of Fig. 5.

Fig. 9 is an elevational sectional view corresponding to Fig. 3 but showing the form of my invention in which the equalizing means is arranged in the lower part of the derrick.

Figs. 10 and 11 are views illustrating an alternative form of the invention.

Fig. 12 is a fragmentary sectional view taken on the line 12—12 of Fig. 3 showing the details of construction of the base and the screw means employed in the removable leg.

5 Referring to the drawings in detail and particularly to Figs. 1 to 8 inclusive, I will describe the preferred form of my invention.

The derrick in which my invention is incorporated has a base construction 11, a 10 crown construction 12, and a plurality of leg constructions 14. According to usual derrick practice, there is a leg construction placed in each corner of the derrick, and each 15 leg construction extends from a corner of the base construction 11 to a corner of the crown construction 12. In view of the fact that the four leg constructions 14 are identical both in construction and operation, in the ensuing 20 description I will describe the leg construction in the singular number, but it is to be understood that the description applies equally well to the other three leg constructions of the derrick.

Referring particularly to Figs. 3 and 4, 25 each leg construction includes a main leg 16 which is preferably made from an angle bar and installed in the derrick with the flanges of the angle bar extending parallel to the sides of the base construction 11 and the 30 crown construction 12 which are of rectangular shape. The lower end of the main leg 16 extends into a corner member 18 of the base construction 11 and is rigidly secured thereto by suitable bolts 19. The upper end of the 35 main leg 16 extends within a headpiece 20 of the crown construction 12, there being a headpiece 20 arranged at each corner thereof. The headpiece 20 includes a pair of upright walls 21 which extend perpendicularly to each other and which are engaged by the flanges of the main leg 16. The main leg 16 is held in position against the upright walls 21 by bolts 23 which extend through vertically elongated slots 24 of the main legs 16 40 and also through openings provided in the upright walls 21.

The construction which I have just described includes what is ordinarily considered the permanent parts of the derrick.

50 This is the construction which is used not only during the drilling operations of the well but is used during pumping operations in the well. As previously mentioned, the derrick is not called upon to handle the enormous 55 loads during pumping operations which it is called upon to withstand during the drilling of the well. The derrick construction as described at this point is not strong enough or rigid enough to support the

60 load and strain imposed during the drilling of the well, for the reason that the main legs 16 are made only heavy enough to properly handle the loads imposed on the crown construction 12 during pumping operations. 65 During the drilling operations of the well it

is necessary to utilize an auxiliary leg 25 which forms a part of the leg construction 14. As illustrated, the auxiliary leg is preferably tubular in cross section and is conveniently positioned within the leg 16, as 70 best shown in Fig. 8. The auxiliary leg may be retained in this position by suitable holding devices 26. The lower end of the auxiliary leg is provided with a jack means whereby it is adjustable in length. Fitted into the tubular part of the auxiliary leg 25 is a nut 27 which threadedly receives a screw 28. The screw 28 has a head 29 which rests in a socket 30 provided by the corner piece 18. By rotating the screw 28, which is done by applying a turning bar to the head 29, the screw may be operated, thus changing the length of the auxiliary leg 25. Placed between the nut 27 and the head 29 is a plurality of horseshoe-shaped shims 31 which are so placed after the adjustment has been made, in order that they may take the load imposed on the auxiliary leg 25 and relieve the screw 28 of this burden. A protective sleeve 33 may be provided for enclosing the parts of the jack.

Referring to Fig. 5, the upper ends of the main and auxiliary legs are provided with a semi-spherical bearing member 35 and a semi-cylindrical bearing member 36 respectively, which members may be secured to their respective legs by welding or any other suitable means. These bearing members 35 and 36 are adapted to be seated in a semi-spherical seat 37 and a semi-cylindrical seat 38 respectively of an equalizing member or proportioning member 39. The equalizing member or proportioning member 39 has an upper semi-spherical bearing face 41 which seats on a semi-spherical seat 42 provided by the headpiece 20. The semi-spherical bearing face 41 and seat 42 are generated around a point 43 which is in substantially the same horizontal plane X—X as the centers 44 and 45 around which the bearing faces of the bearing members 35 and 36 are generated. The point 43 is the fulcrum point around which the equalizing member or proportioning member 39 swings. The weight of the crown is applied from the crown to the equalizing member or proportioning member 39 and from the equalizing member or proportioning member 39 to the main and auxiliary legs 16 and 25, and the load is distributed to the two legs according to the respective lengths of the lever arms A and B. It will be seen that the relative loads carried by the two legs may be changed by changing the relative lengths of the lever arms A and B.

115 For the purpose of retaining the equalizing member or proportioning member 39 in position to be engaged by the main and auxiliary legs prior to the installation of these legs, I provide the equalizing member or proportioning member 39 with depending lugs 120

47 having vertically elongated openings 48 through which a retaining bar 49 is extended, this retaining bar 49 being held by side walls 50 of the headpiece 20. The depending lugs 5 are provided with vertically elongated openings in order that all of the load may be transferred from the headpiece to the equalizing member or proportioning member 39 by reason of the engagement of the seat 42 10 and the face 41.

In Fig. 4 I illustrate the position of the parts prior to the installation of the auxiliary leg 25 or after it has been removed. It will be seen that the equalizing member or 15 proportioning member 39 is in an extreme tilted position due to the absence of the auxiliary leg 25, and at this time a stop lug 51 formed at the outer part of the equalizing member or proportioning member 39 is in 20 engagement with a wall 52 of the headpiece 20 in order to prevent further movement of the equalizing member or proportioning member 39.

For the purpose of explaining the operation of the invention, let us assume that the derrick has been assembled to the point shown in Fig. 4 and that the auxiliary leg 25 is now to be installed. The jack at the lower end of the auxiliary leg is operated so as to shorten 25 the leg in order that it may be placed so that the bearing member 36 may be placed in the seat 38 and the head 29 of the jack may be placed in the seat 30. The workman may then place the holding devices 26 to prevent 30 the auxiliary leg from falling from place. The jack is then operated to elongate the auxiliary leg 25 in order that it may take its predetermined part of the load carried by the crown construction 12. As the jack is 35 operated and the auxiliary leg 25 elongated, the upper end of the auxiliary leg moves upward and the bearing member 36 is brought into engagement with the seat 38 of the equalizing member or proportioning 40 member 39. The equalizing member or proportioning member 39 is then swung in a counter-clockwise direction, and a portion of the weight is transferred from the main leg to the auxiliary leg so that the two legs 45 operate in supporting the load imposed on the crown of the derrick. When the auxiliary leg has been lengthened, as shown in Fig. 3, the equalizing member or proportioning member 39 will occupy a normal position 50 and will automatically proportion the amount of load to be imposed on either of the main or auxiliary legs. During the time 55 that this adjustment is made, there must be a relative movement between the crown construction and the main legs, and for this reason the upper ends of the main legs are provided with vertically elongated slots 24 through which the bolts 23 are extended.

The equalizing member or proportioning member 39 is provided with the extensive

bearing face in order that it may be fully capable of transferring the enormous loads to the legs of the derrick. This bearing face is made cylindrical in order that the equalizing member or proportioning member 39 will 70 swing around a horizontal axis on which the point 43 is located. The upper end of the main leg and the equalizing member or proportioning member 39 are provided with semi-spherical bearings in order that the 75 equalizing member or proportioning member 39 may freely adjust itself to compensate for any slight disalignment of either of the legs. If desired, both bearing members 35 and 36 may be semi-spherical.

I prefer to place the equalizing member or proportioning member 39 in the upper part of the derrick because of the fact that during the placement or removal of the auxiliary leg 25 it is necessary only to vertically move 80 the crown of the derrick.

The main and auxiliary legs, as shown in Fig. 3, are in the positions which they occupy during the drilling of the oil well when enormous strains are imposed on the derrick. After the well has been drilled and the pumping apparatus installed, the crown is called upon to support the relatively light tubings which are used during pumping. At 85 this time the auxiliary leg is removed, and the parts occupy the position shown in Fig. 4. The auxiliary leg is removed by operating the jack member so as to shorten the auxiliary leg in order that the equalizing member or proportioning member 39 may swing into 90 the position shown in Fig. 4 so that the entire load will be carried by the main leg 16 and so that the auxiliary leg may be conveniently removed upon detaching the devices 26.

In Fig. 9 I show a form of my invention in which the equalizing means or proportioning member is placed in the lower part of the derrick. The upper ends of the main and auxiliary legs 16 and 25, respectively, are secured in the headpiece 20, as shown, and may be immovable relative thereto. The lower end of the main leg 16 is provided with the vertically elongated slots 24 through 100 which the bolts 23 are extended. The adjustment means at the lower end of the auxiliary leg 25 is provided with the semi-cylindrical bearing 36 and engages the equalizing member or proportioning member 39. The semi-spherical seat 42 in this form of the invention is provided by the upper wall of the 105 corner piece 18.

The operation of this form of my invention is identical with that of the form shown in Figs. 1 to 8 inclusive. When placing or removing the auxiliary leg 25, it is necessary to raise or lower the entire derrick structure with the exception of the base construction 11, rather than only the crown construction 11, as in the first form of my invention.

In the form of my invention shown in Figs. 10 and 11 the auxiliary leg 25 is of a predetermined length and is not adjustable in length. The equalizing member or proportioning member 39 has an ear 60 projecting outwardly therefrom through which a jack screw 61 is screwed. The jack screw may be advanced through the ear 60 so as to engage the headpiece 20 and to swing the 10 equalizing member or proportioning member 39 into the position shown in Fig. 10. The auxiliary leg 25 may then be installed by placing the lower end or head 29 in the seat 30 and then swinging the upper end through 15 the position shown in Fig. 10 into the position shown in Fig. 11. The jack screw is then rotated to permit the equalizing member or proportioning member 39 to be released so that it may swing into equalizing position, as 20 shown in Fig. 11.

I consider my invention to be broadly novel in the provision of a derrick having a double leg construction in combination with means for automatically imposing a predetermined 25 proportion of the load on each leg, in combination with means permitting an easy installation or removal of the auxiliary leg.

My invention is further novel in the provision of the lengthening means, and as an 30 alternative the jack screw 61, in the combination whereby the auxiliary leg may be removed and replaced and suitably adjusted to position the equalizing member or proportioning member 39 in the most desired position.

I fully understand that various modifications and changes in construction may be made to suit different conditions, and having this in mind I desire that the following 40 claims be broadly construed and that the terms used therein be so construed as to include the mechanical equivalents of the parts shown and described in this specification, which correspond to the terms used.

45 I claim as my invention:

1. A derrick including: an inner leg; an outer leg; proportioning means for automatically proportioning the load between them; and stop means for holding said proportioning means in a certain position.

50 2. A derrick including: an inner leg; an outer leg; proportioning means for automatically proportioning the load between them; and means for lengthening one of said legs 55 for operative engagement with said proportioning means.

3. In a derrick, a base construction, a crown construction, a leg construction extending between said base construction and said 60 crown construction, said leg construction including a pair of legs, the combination of: an automatic load proportioning means in operative relation to said legs for proportioning thereon the load carried by said 65 crown construction; and stop means for hold-

ing said automatic load proportioning means in a given position.

4. In a derrick, a base construction, a crown construction, a leg construction extending between said base construction and said crown construction, said leg construction including a pair of legs, the combination of: a load proportioning means interposed in the derrick structure through which the load carried by the crown construction is transmitted, said 70 load proportioning means engaging said legs and proportioning the amount of said load carried by each of said legs; and stop means for holding said load proportioning means in a given position.

5. In a derrick, a base construction, a crown construction, a leg construction extending between said base construction and said crown construction, said leg construction including a pair of legs, said legs being 75 adapted to transmit from said crown construction to said base construction the load carried by said crown construction, the combination of: a load proportioning means supported by one of said constructions and fulcruming thereon, said legs engaging said load proportioning means on opposite sides of said fulcrum; and screw means operatively connected to said load proportioning and another part of the derrick for restraining said 80 load proportioning means in non-operative position.

6. In a derrick the combination of: a crown construction; a primary leg; a secondary leg; load proportioning means normally engaging 100 said legs for distributing the load between them; and means for holding said load proportioning means in such a position that one of said legs may be installed or removed.

7. In a derrick the combination of: a crown construction; a primary leg; a secondary leg; load proportioning means normally engaging 105 said legs for distributing the load between them; and means for adjusting the length of one of said legs for changing the relative position of said leg and said proportioning means.

8. In a derrick the combination of: a crown construction; a primary leg; a secondary leg; load proportioning means normally engaging 110 said legs for distributing the load between them; and means for limiting the movement of said load proportioning means in one direction.

9. In a derrick the combination of: a crown construction; a primary leg; a secondary leg; load proportioning means normally engaging 115 said legs for distributing the load between them; means for limiting the movement of said load proportioning means in one direction; and means for adjusting the length of one of said legs for changing the relative position of said leg and said proportioning means.

10. A derrick comprising: an inner leg; an 120

- outer leg; load proportioning means engaging each of said legs; and stop means for holding said load proportioning means in a certain position.
- 5 11. In combination with a primary leg, a secondary leg, and a thrust receiving member of an oil well derrick: a thrust dividing device adapted to divide the thrust of said member and transmit it in definite proportions to each of said legs; and means for adjusting the effective length of one of said legs so that said device can be made fully operative in the event that said leg is not initially of the proper length.
- 10 12. In combination with a primary leg, a secondary leg, and a thrust receiving member of an oil well derrick: a thrust dividing device adapted to divide the thrust of said member and transmit it in definite proportions to each of said legs; means constraining said device to transmit the entire thrust to one leg if the other leg is absent or ineffective; and means for adjusting the effective length of one of said legs so that said device can be made fully operative in the event that said leg is not initially of the proper length.
- 15 13. In combination with a primary leg, a secondary leg, and a thrust receiving member of an oil well derrick: a thrust dividing device adapted to divide the thrust of said member and transmit it in definite proportions to each of said legs; and means constraining said device to transmit the entire thrust to one leg if the other leg is absent or ineffective.
- 20 14. In combination with a primary leg, a secondary leg, and a thrust receiving member of an oil well derrick: an automatic proportioning device fulcrumed on said member and engaged at definite lever arms on either side of said fulcrum by said legs so that it can rock about said fulcrum and divide said thrust in definite proportions between said legs; and means for limiting the amount of said rock which will occur if one of said legs is absent or ineffective.
- 25 15. In combination with a primary leg, a secondary leg, and a thrust receiving member of an oil well derrick: an automatic proportioning device fulcrumed on said member and engaged at definite lever arms on either side of said fulcrum by said legs so that it can rock about said fulcrum and divide said thrust in definite proportions between said legs; and means for adjusting the effective length of one of said legs so that said device will be effective if said leg is not initially of the proper length.
- 30 16. In combination with a primary leg, a secondary leg, and a thrust receiving member of an oil well derrick: an automatic proportioning device fulcrumed on said member and engaged at definite lever arms on either side of said fulcrum by said legs so that it can rock about said fulcrum and divide said thrust in definite proportions between said legs; and means for limiting the amount of said rock which will occur if one of said legs is absent or ineffective.
- 35 17. In combination with a primary leg, a secondary leg, and a thrust receiving member of an oil well derrick: a thrust dividing device adapted to divide the thrust of said member and transmit it in definite proportions to each of said legs; and means for adjusting the effective length of one of said legs so that said device can be made fully operative in the event that said leg is not initially of the proper length.
- 40 18. In combination with a primary leg, a secondary leg, and a thrust receiving member of an oil well derrick: a thrust dividing device adapted to divide the thrust of said member and transmit it in definite proportions to each of said legs; means constraining said device to transmit the entire thrust to one leg if the other leg is absent or ineffective; and means for adjusting the effective length of one of said legs so that said device can be made fully operative in the event that said leg is not initially of the proper length.
- 45 19. In combination with a primary leg, a secondary leg, and a thrust receiving member of an oil well derrick: an automatic proportioning device fulcrumed on said member and engaged at definite lever arms on either side of said fulcrum by said legs so that it can rock about said fulcrum and divide said thrust in definite proportions between said legs; and means for limiting the amount of said rock which will occur if one of said legs is absent or ineffective.
- 50 20. In combination with a primary leg, a secondary leg, and a thrust receiving member of an oil well derrick: an automatic proportioning device fulcrumed on said member and engaged at definite lever arms on either side of said fulcrum by said legs so that it can rock about said fulcrum and divide said thrust in definite proportions between said legs; and means for adjusting the effective length of one of said legs so that said device will be effective if said leg is not initially of the proper length.
- 55 21. In combination with a primary leg, a secondary leg, and a thrust receiving member of an oil well derrick: an automatic proportioning device fulcrumed on said member and engaged at definite lever arms on either side of said fulcrum by said legs so that it can rock about said fulcrum and divide said thrust in definite proportions between said legs; and means for limiting the amount of said rock which will occur if one of said legs is absent or ineffective.
- 60 22. In combination with a primary leg, a secondary leg, and a thrust receiving member of an oil well derrick: a thrust dividing device adapted to divide the thrust of said member and transmit it in definite proportions to each of said legs; and means for adjusting the effective length of one of said legs so that said device can be made fully operative in the event that said leg is not initially of the proper length.
- 65 23. In combination with a primary leg, a secondary leg, and a thrust receiving member of an oil well derrick: a thrust dividing device adapted to divide the thrust of said member and transmit it in definite proportions to each of said legs; means constraining said device to transmit the entire thrust to one leg if the other leg is absent or ineffective; and means for adjusting the effective length of one of said legs so that said device can be made fully operative in the event that said leg is not initially of the proper length.
- 70 24. In combination with a primary leg, a secondary leg, and a thrust receiving member of an oil well derrick: an automatic proportioning device fulcrumed on said member and engaged at definite lever arms on either side of said fulcrum by said legs so that it can rock about said fulcrum and divide said thrust in definite proportions between said legs; and means for limiting the amount of said rock which will occur if one of said legs is absent or ineffective.
- 75 In testimony whereof, I have hereunto set my hand at Los Angeles, California, this 11th day of April, 1930.
